J. SOSS,

HINGE

APPLICATION FILED MAR. 7, 1921.

1,385,800.

Patented July 26, 1921.

Fig. 1.

FIG. 2.

FIG. 3.

This technical drawing illustrates a mechanical assembly. On the left, a base plate is shown with various components labeled: 17 (two circular holes), 24 (two circular holes at the bottom), 5 (a slot), 26 (a central slot), 20 (a slot on the right), 23 (a slot on the right), 19 (a slot on the right), 22 (a slot on the left), 26 (a slot on the left), 6 (a slot on the left), 34 (a central slot), and 26 (a slot at the bottom). On the right, a vertical rod assembly is depicted, consisting of a rod 21 with a slot 26, a sleeve 20, and a base 22. The base 22 has a slot 17 and a slot 19. The rod 21 has a slot 26 and a base 21 with a slot 20.

Inventor
Joseph Soss

By his Attorneys

Edgar Gates B.

UNITED STATES PATENT OFFICE.

JOSEPH SOSS, OF NEW YORK, N. Y.

HINGE.

1,385,800.

Specification of Letters Patent. Patented July 26, 1921.

Application filed March 7, 1921. Serial No. 450,160.

To all whom it may concern:

Be it known that I, JOSEPH Soss, a citizen of the United States, and residing at New York, in the county of New York and State 5 of New York, have invented certain new and useful Improvements in Hinges, of which the following is a specification, such as will enable those skilled in the art to which it appertains to make and use the same.

- 10 This invention relates to hinges and the object of the invention is to provide an improved hinge butt construction composed of two or more detachably connected parts fashioned from sheet metal and which are so 15 constructed as to hold the separate parts of said hinge butt, when assembled, rigidly in position or against rattling when subjected to vibrations, and with this and other objects in view the invention consists in a 20 hinge butt of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

30 Figure 1 is a side elevation of the separate parts of a hinge and showing a face view of my improved hinge butt;

Fig. 2 a partial section on the line 2—2 of Fig. 1;

35 Fig. 3 a partial section on the line 3—3 of Fig. 2;

Fig. 4 a face view of one of the parts of my improved hinge butt;

Fig. 5 a section on the line 5—5 of Fig. 4;

40 Fig. 6 a section on the line 6—6 of Fig. 4;

Fig. 7 a view similar to Fig. 3 but showing a modification;

Fig. 8 a view looking in the direction of the arrow 8 of Fig. 7, with part of the construction broken away; and

Fig. 9 a plan view of a part of a hinge butt shown in Figs. 7 and 8.

In Figs. 1 to 3 inclusive, I have indicated at 10 in dotted lines a part of a door frame and at 11 a part of a door or other swinging member. Mounted in connection with the door 11 is a hinge butt 12 which, in the form of construction shown, comprises an attaching plate 13 and a hook-shaped arm 14, the 50 free end of which is tubular in form as shown at 15 in Fig. 2.

The hinge butt 12 forms no part of this invention and is merely shown to illustrate a complete hinge, and in Figs. 1 to 6 inclusive, I have shown at 16 one form of my improved hinge butt which, in the construction shown, is mounted in connection with the door frame 10. The hinge butt 16 comprises an attaching plate 17 and a substantially U-shaped supporting member 18.

The attaching plate 17 is shown in detail in Figs. 4 to 6 inclusive, and said plate is fashioned from a strip of metal, the central portion of which is depressed to form an elongated recess 19 in the outer face thereof, the depth of said recess being approximately two-thirds of that of the thickness of said plate as clearly shown in Figs. 5 and 6, and the backwardly pressed portion 20 which is of the same thickness as that of the plate 17 is of slightly less dimensions than the dimensions of the recess 19, this result being produced by suitable dies and the rear corner portion of the plate between the backwardly pressed portion 20 and the plate 17 proper is rounded to a slight extent as shown at 21 to give strength to the connection between these parts. The backwardly pressed portion 20 is cut out to form an approximately rectangular aperture 22, and the plate 17 is provided at one side portion thereof with a cut-out or apertured portion 23 which opens into the aperture 22 but is of less vertical dimensions than the aperture 20 as is clearly shown in Fig. 4 of the drawing. The free corner portions of the plate 17 are also provided with countersunk screw-apertures 24 through which screws or other attaching devices 25 may be passed for mounting said plate in connection with a suitable support.

After the aperture 22 has been formed in the backwardly pressed portion 20 of the plate 17 the remaining parts thereof form attaching means for the supporting members 18 of the hinge butt and are provided with threaded apertures 26 approximately centrally thereof.

The supporting member 18 is also preferably fashioned from a strip of sheet metal bent centrally to form an inwardly directed U-shaped body 27 which is curved laterally to a slight extent as shown at 28 in Fig. 2 of the drawing, and the end portions 29 of the member 18 are provided with countersunk screw apertures 30 through which screws or similar attaching devices 31 are

adapted to pass and into the threaded apertures 26 of the plate 17, or the backwardly pressed portion 20 thereof in securing the member 18 in connection with the plate 17.

It will be noted that the end portions 29 of the member 18 are adapted to fit snugly within the end portions of the recess 19 in the plate 17, and the outside vertical dimensions of the member 18 will be such as to snugly fit in the aperture 22 of the backwardly pressed portion 20 so that when the member 18 is secured to the plate 17 by the screws 31, the movement of said parts one upon another will be obviated when subjected to vibrations, and this will also relieve the strain upon the screws 31 and prevent the loosening thereof.

The top and bottom walls of the backwardly directed U-shaped portion 27 of the member 18 are provided with countersunk apertures 32, one of which is shown in full lines in Fig. 3 of the drawing, and in securing the hinge butts 12 and 16 together a pin 33 is passed through the tubular portion 15 of the hook-shaped arm 14, and one or both ends thereof, riveted into the countersunk recesses 32 thus connecting the supporting member 18 with the hinge butt 12. It will be noted that with this construction the door or swinging member may be detached from the door frame, or the plate 17, secured thereto by simply removing the screws 31.

The construction shown in Figs. 7 to 9 inclusive is the same in all respects as that of the construction in Figs. 1 to 6 inclusive, except that the backwardly pressed portions 20 of the plate 17 are provided with notches or recesses 34 which are indicated in dotted lines in Figs. 4, 5 and 6 and shown in full lines in Figs. 7 and 8, and the member 18 in this form of construction, or the top and bottom walls of the backwardly directed U-shaped portion 27 are provided, adjacent to the end portions 29, with spring members 35 which are stamped from said top and bottom plates as is clearly shown in Figs. 7 and 9 of the drawing.

The transverse dimensions of the spring members 35 are such as to permit of the passage of said spring members into the notches or recesses 34 and to fit snugly therein. It will also be apparent that in connecting the member 18 with the plate 17, as hereinbefore set out, the backward or inward movement of the member 18 by the screws 31 depress the spring members 34 thus placing said parts under tension which will in itself prevent the rattling or movement of the parts 17 and 18 one upon another.

It will be apparent that while the members 35 are described as spring members, these members may merely be projections formed in the top and bottom walls of the hook-shaped portion 27 of the member 18,

the dimensions and form of said members being such as to snugly fit in the notches or recesses 34, but I prefer that these members should have a slight spring action. It will also be understood that while I have shown certain details of construction for carrying my invention into effect that I am not necessarily limited to these details, and various changes in and modifications of the construction herein shown and described may be made, within the scope of the appended claims, without departing from the spirit of my invention or sacrificing its advantages.

Having fully described my invention, what I claim as new and desire to secure by Letters Patent, is:—

1. In a hinge butt of the class described an attaching plate fashioned from sheet metal and provided with an elongated recess in one face thereof formed by pressing the material of said plate inwardly, the depth of said recess being less than the thickness of the material of said plate and the inwardly pressed portion being provided with an aperture.

2. In a hinge butt of the class described, an attaching plate fashioned from sheet metal and provided with an elongated recess in one face thereof formed by pressing the material of said plate inwardly, the depth of said recess being less than the thickness of the material of said plate and the transverse and vertical dimensions of said inwardly pressed portion being less than the corresponding dimensions of said recess.

3. In a hinge butt of the class described, an attaching plate fashioned from sheet metal and provided with an elongated recess in one face thereof formed by pressing the material of said plate inwardly, the depth of said recess being less than the thickness of the material of said plate and the transverse and vertical dimensions of said inwardly pressed portion being less than the corresponding dimensions of said recess, and the central part of said inwardly pressed portion being provided with an aperture.

4. A hinge butt of the class described comprising an attaching plate and a supporting member detachably mounted in connection with said plate, said attaching plate being provided in one face thereof with an elongated recess formed by pressing the material of said plate inwardly, the inwardly pressed portion being provided with an aperture, and said supporting member being adapted to fit in the recess of said attaching plate and being provided with a part which extends through the aperture in the inwardly pressed portion of said plate.

5. A hinge butt of the class described comprising an attaching plate and a sup-

porting member detachably mounted in connection with said plate, said attaching plate being provided in one face thereof with an elongated recess formed by pressing the material of said plate inwardly, the inwardly pressed portion being provided with an aperture, and said supporting member being adapted to fit in the recess of said attaching plate and being provided with a part which extends through the aperture in the inwardly pressed portion of said plate, and that part of the supporting member which passes through the aperture in said plate being provided with laterally projecting members adapted to operate in connection with notches or recesses in the inwardly pressed portion of said plate for holding said parts against movement one upon another.

6. A hinge butt of the class described comprising an attaching plate and a supporting member detachably mounted in connection with said plate, said attaching plate

being fashioned from sheet metal and provided in one face thereof with a recess formed by pressing the material of said plate inwardly, the depth of said recess being less than the thickness of the material of said plate, the inwardly pressed portion being provided with an aperture through which said supporting member is adapted to pass, and tensional means fashioned from said supporting member and adapted to cooperate with the inwardly pressed portion of said attaching plate for holding said parts against movement one upon another when attached.

In testimony that I claim the foregoing as my invention I have signed my name in presence of the subscribing witnesses this 5th day of March 1921.

JOSEPH SOSS.
